UNITED STATES PATENT OFFICE

JOSEPH F. RUSSELL, OF OAKLAND, CALIFORNIA, ASSIGNOR TO MODERN FOUNDRY AND PATTERN WORKS, OF OAKLAND, CALIFORNIA, A CORPORATION OF CALIFORNIA

RINSING AND DRYING APPARATUS

Application filed March 21, 1927. Serial No. 176,979.

This invention relates to improvements in clothes rinsing and drying apparatus, and has for its primary object the provision of an improved apparatus which may be attached to the washing receptacle of a washing machine, to provide means for the convenient rinsing and drying of the washed clothing.

In the development of the present apparatus, particular attention has been given to the arrangement of the supporting members for the washing, and the rinsing and drying receptacles forming a part thereof, and the arrangement shown has been found to be exceptionally satisfactory in that one of the three supporting legs is mounted in axial alignment with the axis of rotation of the rinsing and drying receptacle. This arrangement of the supporting legs provides a solid support for both the washing and the rinsing and drying receptacles and practically eliminates vibration due to the centrifugal action of the rinsing and drying receptacle when in operation.

All types of rinsing and drying devices that operate on the centrifugal principle are more or less subject to considerable vibration, and it is one of the important features of the present invention to reduce such vibration to a minimum by the proper positioning of the supports for the apparatus. The supports are provided with castors and one of the castors is arranged to render all the castors either mobile or immobile as desired.

A novel driving means has also been utilized in the present construction and includes a friction drive and a clutch mechanism arranged in such a manner that the driving power for the actuation of the rinsing and drying receptacle is derived from the washing machine power unit, without in the least detracting from its function of driving the washing machine impeller.

A novel drain means is also included in the present construction and consists of a collecting ring revolvably supported in an annulus carried by the washing receptacle of the washing machine, and which is provided with a drain spout adapted to be swung to any radial position by the rotation of the collecting ring relative to the supporting annu-

lus, to position the spout to drain any water from said collecting ring which may be deposited therein by the centrifugal action of the rinsing and drying receptacle.

The important object of my invention is to provide a combined rinsing and drying apparatus which is coactively associated with a washing machine, the two being combined in such a manner that the supporting legs and power unit are common to both, and that one of said supporting legs is arranged in axial alignment with the rinsing and drying apparatus and provides means for rendering the entire apparatus either mobile or immobile, as desired.

Another object of my invention is to provide a rinsing and drying apparatus of the character designated which is comparatively simple in construction, practically vibrationless, sufficient in operation, durable, and easily handled.

Another object of the invention is to provide an apparatus of the character designated which embodies a novel driving means including a simplified clutch mechanism.

An additional object of importance is the provision of a water-collecting and drainage ring for the rinsing receptacle which permits a manual rotative movement thereabout in any radial direction to drain the same, even when either or both the washing and rinsing receptacles are in operation, thus effecting the removal of suds and dirty water and the introduction of clear rinsing and blueing water and its expulsion without the necessity of stopping the washing machine and the rinsing receptacle at all.

Another object of the invention is to provide an improved drain board with a collector ring arranged to receive the water as discharged from the rinsing and drying receptacle, and in turn discharge said water into any receptacle.

Other objects and advantages will be apparent with reference to the subjoined specification and accompanying three sheets of drawings, in which:

Figure 1 is a vertical sectional view showing my improved rinsing and drying apparatus in combination with the washing re-

ceptacle of a washing machine with which it is preferably associated; the section being indicated by the line 1—1 of Figure 2;

Figure 2 is a top plan view of the apparatus showing mainly the collecting ring and spout which in the present instance is shown positioned directly over the washing receptacle of the washing machine, parts being broken away to expose the rinsing and drying receptacle;

Figure 3 is a greatly enlarged sectional detail of the driving means, clutch, and supporting means for the rinsing and drying receptacle;

Figure 4 is a bottom plan view of the clutch-shifting disc; and

Figure 5 is a detail view illustrating the mobile position of one of the castors which is shown in immobile position on the rinsing and drying apparatus supporting leg in Figure 1.

Figure 6 is a minified front elevation of the complete rinsing, drying and washing apparatus.

Referring to the drawings in detail and in particular to Figure 1 in which the preferred embodiment of my invention is shown, the number 10 in a general way designates the rinsing and drying apparatus and 11 the washing receptacle with which the apparatus is associated. The driving unit 12 is shown in dotted lines in Figure 2 and consists of an electric motor connected to the impeller driving means in any suitable manner, and to the rinsing and drying receptacle by means of the driving connections 13, friction driving means 14, and clutch 15.

The washing receptacle 11 is preferably provided with two supporting legs 8 and 9 which are secured thereto in any suitable manner and have castors at their lower ends. The rinsing and drying receptacle 10 is supported by a third supporting leg 16 which is provided at its lower end with a castor 17, and the supporting shank of this castor is arranged in axial alignment with the axis of rotation of the rinsing and drying receptacle 10, as shown in Figure 1. The washing receptacle 11 is provided with a cast member 18 which is secured to the underside thereof by means of depending lugs 19 and 20 having openings formed therein for bolts 21 and 22, that rigidly clamp the member 18 in position. Said member 18 is provided with an integrally formed bearing boss 23 and a second bearing boss 24 mounted in horizontal alignment therewith and forming bearing supports for a drive shaft 25.

A belt pulley 26 is mounted upon the inner end of shaft 25 and is provided with a V-shaped groove 27, adapted to receive a round driving belt 28 which connects the motor pulley 29 to the washing machine impeller driving pulley 30, said pulley 26 merely frictionally engaging the top section of the belt 28,

as shown in Figure 1, which provides an efficient drive for the rinsing and drying receptacle 10. The outer end of shaft 25 is reduced as indicated at 31, and is provided with a bevelled friction disc 32 which is held in place by a nut 33 screwed upon the threaded end of said shaft. The cast member 18 is provided with extensions 34 and 35 that terminate in an integrally formed and vertically-disposed bearing boss 36, which is of elongated shape and is provided with a vertical bore 37 into which is fitted a vertically-disposed supporting spindle 38, held in rigid relation with the boss 36 by means of set screw 39.

The supporting leg 16 is provided at its upper end with an integrally formed lug 40, through which a vertical bore 41 extends and into which the lower end of the spindle 38 is seated, the leg being rigidly secured to the lug by means of a set screw 42. An extension 43 of the leg 16 bears against the under edge of a flange 44 integrally formed with the boss 36 and provides an additional bracing means for the cast member 18 and washing receptacle 11.

The rinsing and drying receptacle 10 preferably consists of a sheet metal container having a bottom 45 and an upwardly and outwardly flared side wall 46 terminating in a rolled upper edge 47. The bottom 45 of the container 10 is provided with a concentrically-disposed flange 48 integrally formed with a centrally-disposed hollow pedestal 49 extending upwardly within the container, the said flange 48 being bolted to the bottom of the container by the bolts 50. The underside of the bottom 45 of the container is provided with a disc 51 through which the bolts 50 extend, and said disc is provided with two tangs 52 and 53 punched out of its central section and depending therefrom to form part of the clutch mechanism hereinafter described.

The container 46 is suspended upon the spindle 38 by means of a ball race having one member 54 thereof secured in the reduced upper end 55 of the pedestal 49 by means of spring rings 56 and 57, and the other member 58 thereof is secured to the reduced upper end 59 of the spindle by the nut 60. The two members 54 and 58 are grooved to receive a row of ball bearings 61 which revolvably support the container upon the spindle 38.

The lower end of the pedestal 49 is provided with a concentrically-disposed cylindrical extension 62, which extends through an opening formed in the bottom 45 of the container and is exteriorly and interiorly finished to provide an outer bearing surface for the clutch member 63 and an interior housing for a shell 64, which bears a plurality of roller bearing members 65 that surround the spindle 38 and which bearing members form a lower main bearing about which the container 46 rotates.

The clutch member 63 consists of a sleeve 66 having a central bore 67 forming a sliding fit upon the exterior surface of the extension 62, and having formed at its lower end a bevelled friction disc 68 which is adapted to normally engage the friction disc 32 mounted upon the shaft 25.

A compression spring 69 is mounted in the lower end of the bore 67 of the clutch member (and bears against the lower end of the extension 62 of the pedestal and against a shoulder 70 formed in the extreme lower end of said bore 67, and tends to normally urge said bevelled friction disc into contact with the bevelled disc 32.

The clutch member 63 is provided with a plurality of radially-arranged ribs 71 that terminate in a common plane with that of the upper end of the sleeve 66, and form means adapted to intercept the tangs 52 and 53 to rotate the receptacle 46.

The shifting means for disengaging the bevelled discs 68 and 32 consists of a flat circular disc 72, Figure 4, provided with a centrally disposed opening 73 adapted to loosely fit the exteriorly finished surface 74 of the boss 36 and to rest upon the shoulder 75 formed thereon. The upper face of the disc is provided with a cork washer 76 secured thereto in any convenient manner, and is adapted to engage the underside of the bevelled member 68 to shift said member out of contact with the bevelled member 32 and to additionally provide braking means to stop the spinning action of the container 46.

The elevating of the disc 72 is accomplished by means of integrally cast cam members 77 and 78, Figs. 3 and 4, which are provided with tapered sections 79 and 80 and straight sections 81 and 82 terminating in stop lugs 83 and 84. The said members 77 and 78 are adapted to normally rest on opposite sides of the ribs 85 formed integral with the cast extensions 34 and 35 and the boss 36 of the frame 18, and when moved toward said ribs by the swinging movement of the handle 72', are adapted to elevate the said disc until the straight sections 81 and 82 rest upon the upper edges of the ribs 85, in which position the member 68 is disengaged from the member 32, and the container is immediately stopped by the braking action of the cork disc 76 frictionally engaging the underside of member 68.

The upper edge of the washing receptacle 11 is provided with a cast member 86, having supporting brackets 87 which are rigidly bolted to the washing receptacle by bolts 88 and 89, Figure 2, and in which an enlarged circular opening 88' is formed to receive an annulus 89' having an annular rib 90 adapted to fit within the opening 88' of the member 86 and adapted for free manual rotary movement relative thereto. The rib 90 is provided with an integrally cast member 91

circumferentially positioned thereabout and curved outwardly and upwardly to form a collecting ring 92 to receive the overflow water from the container 46; the said container being somewhat smaller in diameter than the opening 93 formed in the annulus and adapted to rotate freely therein, as shown in Figure 1.

A plurality of radially-positioned screws 94, only one of which is illustrated are tapped through the annulus rib 90 and engage the underside of the member 86 to prevent the annulus from being removed from the opening 88' of the said member 86.

The member 91 is provided with an integrally formed spout 95, of considerable width in plan but shallow in depth and having a considerable drop to facilitate the draining of the water collected by the collecting ring 92.

As shown in Figure 1, the annulus is provided with a small lug 96 positioned diametrically opposite the spout 95 and adapted to rest upon the upper surface of the member 86 which lug tends to tilt the annulus slightly relative to the horizontal member 86, to cause the water collected by the collecting ring to drain rapidly toward the spout.

A cast cover 97 fits over the upper edge of the annulus, and forms a guard to prevent water from splashing out of the container, when in operation. The cover 97 is provided with a central opening through which the articles may be dropped into the container, and which may be capped when not in use by a sheet metal cap 98, as shown in Figs. 1 and 2.

The castor 17 mounted in the lower end of the supporting leg 16 is of a well-known type, in which the castor center 99 is arranged to be positioned in axial alignment with the spindle 38, as shown in Figure 1, when the yoke center 100 is moved to the position shown to the left of the center-line and which is the immobile position of the castor, and the position in which it remains while the rinsing and drying receptacle is in use. When it is desired to move the apparatus the castor is rendered mobile by swinging the yoke center 100 to the position shown in Figure 5, thus freeing the castor wheel for movement in either direction.

The operation of the rinsing and drying apparatus is as follows:

When it is desired to operate the said apparatus, the wet clothes are first placed in the container through the opening in the annulus, and the driving motor 12 is started which causes the rotation of pulley 26, shaft 25 and friction disc 32, and assuming that the friction disc 68 is held out of contact with the disc 32 by the shifting mechanism, which is the normal position of said disc 68. The handle 72' is next manipulated to drop the disc 68 into contact with the disc 32, which causes the acceleration of the container and

its contents. As soon as the container is sufficiently accelerated the liquid content starts to gyrate toward the rim 47 of the container, and from the rim is thrown into the collecting ring and is drained therefrom by the 5 spout 95.

This operation is continued for several minutes, generally from seven to fifteen, depending upon the quantity of wet material 10 in the container. The shifting mechanism is then operated and the friction disc 68 is raised from the disc 32 and the container stopped, the material being then removed 15 from the container in a practically semi-dry state.

The rinsing of the washed material may be accomplished by placing it in the rinsing container with sufficient cold water for rinsing 20 purposes and the blueing added as usual, whereupon the rinsing water may be drawn off as described.

From the foregoing description taken in connection with the accompanying drawings, the advantages of the construction and 25 method of operation will be readily understood by those skilled in the art to which the invention appertains, and while I have described the principle of operation, together with the device which I now consider to be 30 the best embodiment thereof, I desire to have it understood that the device shown is merely illustrative and that such changes may be made, when desired, as fall within the scope 35 of the appended claims.

Having thus described my invention, I 40 claim as new and desire to secure by Letters Patent of the United States, the following:—

1. In combination with a centrifugal machine having a centrifugal drum rotatable 45 about a vertical axis, a support for said machine including three supporting legs; one of 50 said legs being substantially in line with said axis.

2. In combination with a centrifugal machine having a centrifugal drum rotatable 55 about a vertical axis, a support for said machine including a plurality of not less than three supporting legs; one of said legs being substantially in line with said axis.

3. A centrifugal machine comprising a support, tripod mobilizing means for said support, and a centrifuging drum journaled 60 for movement about a vertical axis in said support; said support terminating in said 65 mobilizing means, and a foot of said mobilizing means being operative in line with the axis of said drum.

4. In combination with a centrifugal machine having a vertical axis of rotation, a 65 portable support for said machine including a plurality of not less than three mobile legs; one of said legs being substantially in line with said axis; and means for immobilizing the last-recited said leg.

5. In combination with a portable cen-

trifugal machine having its main axis of rotation vertical, means for supporting said machine including a caster of the described type having a vertical swivel axis positioned substantially in line with said main axis and 70 having a wheel axis normally skew to said swivel axis for mobility, and adjusting means in said caster for relatively moving said wheel axis into intersecting relation with said swivel axis whereby thrust emanating 75 from said main axis is ineffectual to mobilize said caster.

6. In combination with a machine including an upright and rotatable shaft, a support for said machine comprising a plurality 80 of not less than three supporting feet, one of said feet being operative substantially in the axial line of said shaft.

In testimony whereof, I affix my signature.

JOSEPH F. RUSSELL.
